IDS filed on Nov. 26, 2012 in connection with Design U.S. Pat. No. D680,860, containing the NPL references cited therein.

Primary Examiner — Cynthia Underwood

(74) Attorney, Agent, or Firm — Fulwider Patton LLP

(57) **CLAIM**

The ornamental design for a hinged clamshell food container, as shown and described.

DESCRIPTION

FIG. 1 is a perspective view of the interior of an embodiment of the hinged clamshell food container in an open condition; FIG. 2 is a perspective view of the exterior of an embodiment of the hinged clamshell food container in an open condition;

FIG. 3 is a left side view of the exterior of an embodiment of the hinged clamshell food container in an open condition; FIG. 4 is a right side view of the exterior of an embodiment of the hinged clamshell food container in an open condition; FIG. 5 is a rear view of the exterior of an embodiment of the hinged clamshell food container in an open condition

FIG. 6 is a front view of the exterior of an embodiment of the hinged clamshell food container in an open condition;

FIG. 7 is a bottom view of the exterior of an embodiment of the hinged clamshell food container in an open condition; and,

FIG. 8 is a top view of the exterior of an embodiment of the hinged clamshell food container in an open condition;

The broken lines represent portions of the structure that form no part of the claim.

1 Claim, 6 Drawing Sheets
